UNITED STATES PATENT OFFICE.

JACOB DE MOTT, OF FRENCHTOWN, NEW JERSEY.

RAILROAD-TIE.

SPECIFICATION forming part of Letters Patent No. 339,275, dated April 6, 1886.

Application filed February 6, 1886. Serial No. 191,017. (No model.)

To all whom it may concern:

Be it known that I, JACOB DE MOTT, a citizen of the United States, residing at Frenchtown, in the county of Hunterdon, State of New Jersey, have invented certain new and useful Improvements in Railroad-Ties, of which the following is a specification, reference being had therein to the accompanying drawings.

This invention has relation to railroad-ties, and more particularly to that class of ties which are made of metal, either cast or wrought.

The object of the invention is to provide a tie which can be removed and replaced without detaching any of the adjacent ties, and which is so constructed that when in position the rail is firmly secured to the same and prevented from displacement by ordinary use.

Other objects and advantages will appear in the following description, and the novel features thereof will be particularly pointed out in the claims.

Referring to the drawings, Figure 1 is a side elevation of a tie constructed in accordance with my invention, the rails mounted thereon being shown in cross-section. Fig. 2 is a side elevation of one end of the tie, the rail and rail-securing devices being removed therefrom. Fig. 3 is a plan of the opposite end of the tie with the rail thereon. Fig. 4 is a plan of the rail-securing staple or band, and Fig. 5 is a perspective of the key.

Like letters of reference indicate like parts in all the figures of the drawings.

The tie consists of a central portion, A, and end portions, B B', the whole being cast in a single piece or forged or otherwise formed from wrought metal. In this instance both ends are rounded and provided with recesses B², and with the abutment B³, the face B⁴ of which is recessed in such a manner as to fit more or less snugly the base and web of the rail used in connection with the tie. The recess in the face of the opposite abutment is made to conform to a key, C, and said key is made to conform to the base and web of the rail employed. At one of the inner ends of the recess B² is formed a depression or offset, B⁵, which extends inwardly or transversely in the tie from the bottom of the said recess B². This offset is made for the purpose of receiving the lug C', projecting from the bottom and at one end of the key C.

D represents the rail-securing staple, which is of a form adapted to embrace the end of the tie and to rest wholly within the recess B², while its ends D' are, when heated slightly above red heat, bent over the base of the rails E, so that when said staple cools it shrinks and draws the rail firmly against the abutment or against the key, which is also drawn firmly against the abutment, so that the parts are firmly bound in operative position and against displacement by ordinary use.

The shape of the central portion, A, of the tie may be as desired for any particular purpose, and the bottom of the tie is preferably provided with shoulders A', which are intended to abut against the inner faces of the stone or other suitable foundation, A², upon which the ends B B' rest.

A³ represents holes, which are formed, by casting or otherwise, in the sides of the tie in proximity to that point where the staples D are bent upwardly over and upon the base of the rails, the object and purpose of said holes being to receive and pivotally support any desired form of tool employed in bending the heated staple upon the base.

The purposes of the key C is to permit of the removal of any tie of a series from the rails. It will be noticed that the lug C' (see dotted lines, Fig. 1) abuts against the inner side of one arm of the staple D, so that the key cannot be removed from its position between the rail and the abutment by forcing it across the tie without first cutting and removing the staple. This is preferably done by the use of any desired tool which will sever the same on a diagonal line at any point, preferably at the apex of the bend in the staple while in the recess, so that the cut ends will be in a condition to be again welded together, if desired. When this is done the key can be driven from its position, and when the key is removed the face of the abutment B³ will pass downwardly by the outer edge of the base of the rail, when, by removing the opposite staple, the tie may be moved longitudinally under the rails to detach the opposite abutment from the base of the opposite rail, when the tie may be entirely removed from the rails. In replacing the tie these operations are reversed. The key is inserted, the staples heated, and replaced and bent over the rails, as in the first instance.

The object of placing the staples within recesses is to prevent so far as possible unauthorized tampering with the same to the injury of the track, so that aside from this particular purpose it is not absolutely essential that the staples be seated in any recesses formed in the ends of the ties; and it is also apparent that it is not absolutely necessary that said ends should be rounded, as a square staple could be employed in connection with a square-ended tie.

Having described my invention and its operation, what I claim is—

1. A railroad-tie having an abutment for a rail, and a recess around its ends for the reception of a securing-staple, substantially as specified.
2. The combination of a rail with a tie having an abutment, and a staple arranged about the end of the tie and bent over and shrunk upon the base of the rail, substantially as specified.
3. The combination of a tie having an abutment, a rail, an interposed key, and a staple embracing the end of the tie and bent over and shrunk upon the base of the rail, substantially as specified.
4. A tie having an abutment at each end, a rail arranged against one abutment, a remov-

able key arranged against the other abutment, 30 a rail arranged against the key, and staples arranged to embrace each end of the tie and bent over and upon the bases of the rails, substantially as specified.

5. The combination of a tie having abutments B³ B', the rails E, the key C, and the staples D, embracing the ends of the tie and the bases of the rails, substantially as specified.

6. The combination of the tie having the abutment B³, the rail E, and the staple D, 40 embracing the end of the tie and bent upon the base of the rail at each side of the tie, substantially as specified.

7. The combination of a tie having an abutment, a key having a stop and adapted to fit 45 the abutment and the rail, with a rail, and with a staple adapted to embrace the end of the tie and the base of the rail, and to serve as a stop to the movement of the key in one direction, its movement in the opposite direction being 50 stopped by the tie, substantially as specified.

In testimony whereof I affix my signature in presence of two witnesses.

JACOB DE MOTT.
